UNITED STATES PATENT OFFICE.

JABE CURRY FAUGHENDER, OF PIEDMONT, ALABAMA, ASSIGNOR TO FAUGHENDER & CRUSOE, OF SAME PLACE.

ICE-PLANE.

SPECIFICATION forming part of Letters Patent No. 430,009, dated June 10, 1890.

Application filed June 15, 1889, Serial No. 314,333. (No model.)

To all whom it may concern:

Be it known that I, JABE CURRY FAUGHENDER, of Piedmont, in the county of Calhoun and State of Alabama, have invented a new 5 and Improved Ice-Plane, of which the following is a full, clear, and exact description.

The object of my invention is to produce a simple, cheap, compact, and convenient implement with which ice in large blocks may 10 be operated upon to shave therefrom proper quantities of finely-reduced ice, which may be required in the composition of mixed iced drinks of various kinds.

The invention consists in the construction 15 and arrangement of parts hereinafter described and claimed.

Reference is to be had to the accompanying drawings, forming a part of this specification, in which similar letters of reference indicate 20 corresponding parts in all the figures.

Figure 1 represents a side elevation, partly 25 in section, of the device, showing interior construction of its parts. Fig. 2 is a rear elevation of the implement; and Fig. 3 is a trans- 30 verse sectional elevation of the device, taken on the line $x-x$, Fig. 1.

The stock of the ice-plane is preferably 35 constructed of metal, although hard wood or other material may be utilized in its manu- 40 facture. As will be observed, the form of the plane-stock does not differ essentially in the portion which retains the cutting-tool from 45 an ordinary plane used for smoothing wooden surfaces. In Fig. 1 the shape of the stock is displayed. It consists, essentially, of a base- 50 plate A of sufficient thickness to insure stability. On the top surface of the base-plate A the handle C is secured. This may be of 55 wood or metal. Preferably the latter-named 60 material is employed. Integral with the han- 65 dle C, or affixed thereto at its upper end, the inclined throat-plate D is extended diagonally from the base-plate A, a transverse slot or 70 throat c being formed in the base-plate at the 75 foot and in front of the inclined throat-plate 80 D. A cutting bit or tool E, similar to an ordi- 85 nary wood-plane bit, is placed against the 90 throat-plate D and secured adjustably on it, the 95 plate D and the tool E being slotted to 100 facilitate the adjustable attachment of the

tool upon the throat-plate, the screw-bolt a and winged thumb-nut b being employed in the usual manner to hold the tool in place. While it is not imperative that the cutting-bit E be furnished with an adjustable cap F, 55 it is considered that such a feature, if employed, will render the operation of shaving the ice more satisfactory, as there may be a closer adjustment effected, and consequently finer shavings produced, when the plane-bit is 60 capped, as shown in the drawings; hence it is preferred to so construct the device.

Upon each side of the base-plate A the upright walls B are formed integral with said base-plate. These walls extend upwardly a proper 65 height and are parallel with each other up to a point g, (see Fig. 3,) from which point the vertical walls are sloped inwardly, thus producing inclined inner surfaces on the walls B. The outer faces of the walls B may be made 70 perpendicular throughout their entire height, as represented in the drawings, or to save material it is evident the outer faces of each wall from the point g upward may be made to incline inwardly at the same angle as the inner 75 faces of the walls, and in this way avoid thick- 80 ening up the walls at their upper edges. This latter plan of construction is represented by dotted lines in Fig. 3. From the position given the walls B on each side of the plane- 85 stock a retaining-shoe is formed for the con- 90 venient introduction and retention of the box G. The box just named is preferably con- 95 structed of sheet metal, which may be tinned or galvanized iron, so as to prevent rusting of the same. In form it consists of a rectangu- 100 lar chamber having one end open, the side walls being cut to slope or incline, as shown in Fig. 1, so as to fit neatly against the adjacent face of the throat-plate D when the box G is inserted in place. The side walls of the box G are inclined inwardly near their upper edges, so as to give the box a conformation similar to that of the walls B and cause it to fit as a dovetail in the space afforded between 95 the walls B.

A handle d is attached to the end wall of the box G, as shown in Fig. 1, by which the box may be manipulated to insert or remove it from its position on the stock.

Several different sizes of this implement may be made to render it effective in the shaving of different quantities of ice, as may be required. Usually a comparatively small, 5 light, and neat device of the form herein shown and described will have sufficient capacity to produce the quantity of finely-reduced ice necessary for one or several glasses of 10 iced drinks and effect the reduction speedily. All the shaved ice passing upward through the throat-slot *c* will enter the box *G*, and from thence may be decanted into one or more goblets or drinking-glasses, as may be desired.

15 From the compact form and consequent easy handling of the implement hereinbefore described it is available for use upon a large block of ice that is contained in a refrigerator-chamber, and thus avoid the waste of ice 20 and delay incidental to the use of other devices that require the ice to be first broken into pieces before it can be operated upon by the machine.

The simplicity of construction, low cost of 25 production, convenience in use, and manifest saving in consumption of ice are evident features of advantage pertaining to the within-described ice-plane.

Slight changes in form of the parts of this 30 improved ice-plane may be made and not violate the spirit of my invention—as, for instance, the walls *B* may be made lower than shown in the drawing, or a modified form of sliding connection of the box *G* with the stock 35 of the plane may be substituted, such as an ordinary tongue and groove; or the side walls *B* can be dispensed with and a tongue-and-groove connection of the box-bottom be provided. All these are equivalent means for 40 holding the box *G* in sliding connection with the plane-stock in front of the cutting-bit *E*.

Hence I do not wish to limit the construction of the device to the exact forms shown.

In practice the front end of the base-plate will be slightly upturned or beveled on the 45 under side to enable the plane to pass over the rough surface of the ice.

Having thus described my invention, what I claim as new, and desire to secure by Letters Patent, is—

50

1. The combination, with a plane having a transverse throat or slot through the base of its stock and the cutting-tool projecting downwardly therethrough, of a removable box on the upper side of the base open at its inner 55 end and registering with the said slot in front of the cutting-tool to receive the shaved ice, substantially as set forth.

2. An ice-shaving plane consisting in the base *A*, having a transverse throat or slot 60 therethrough, side walls extending up from the forward end of the base, a handle on the upper side of the rear end of the base, the inclined plate *D*, the cutting-tool resting against the said plate and extending at its cutting- 65 edge downwardly through the said throat or slot, and the removable box between said side walls, substantially as set forth.

3. In an ice-plane, the combination, with a stock having a base-plate, a handle, a throat- 70 plate, a throat-slot, and walls which are adapted to hold in place an ice-receiving box and permit its removal endwise, of the stock of an ice-cutting tool and an ice-receiving box which is removably secured upon the 75 plane-stock in position to receive the ice shaved off by the cutting-bit, substantially as set forth.

JABE CURRY FAUGHENDER.
